UNITED STATES PATENT OFFICE

JOSEPH A. HOEGGER, OF JERSEY CITY, NEW JERSEY

SUPPORTING LEG

Application filed December 2, 1927. Serial No. 237,142.

My invention relates to improvements in supporting legs, and more particularly to the kind of legs which are usually anchored in a stationary position in the floor to carry some super-structure. For example legs of this character are frequently used in toilets to support the various partitions in spaced relation to the floor, but the leg can be used for other purposes, although it is well adapted to the purpose mentioned. When used in connection with toilet partitions I also use a simple strong and handsome means for supporting the partitions on the leg. In any event it is generally an exposed leg. In legs of this character it frequently happens that they need adjustment, or that after the legs and their super-structure which they carry have been installed, the floor or building will settle slightly, and the super-structure will need adjustment. In such cases it is frequently necessary to remove the leg from its floor foundation, which is quite a serious and expensive matter. Moreover these legs are generally symmetrically shaped and adapted to be of an ornamental nature because they are exposed to view.

My invention is intended to obviate these difficulties, and produce a simple form of leg which can be easily secured in the floor, and which can be adjusted readily as to its length, and which further can be made as strong and ornamental as the usual one-piece leg. In carrying out this idea I make the leg in two parts, the lower of which is seated in but easily removable from the floor, make the two parts adjustable in relation to each other, and employ an external sleeve which covers the joint between the two leg members and which thus serves as a brace and can be made ornamental if desired.

Reference is to be had to the accompanying drawings forming a part of this specification, in which similar reference characters indicate corresponding parts in all the views.

Figure 1 is a broken perspective view showing the general application of my improved leg.

Figure 2 is a plan view thereof.

Figure 3 is a longitudinal section on an enlarged scale.

Figure 4 is a broken side elevation of the upper part of the leg, and

Figure 5 is an inverted plan of the seat. 55 The leg is provided with a depressed seat 10 which can be conveniently of sheet metal and which is anchored in the floor 11 which may be of cement, and is held fast by the conventional anchoring device 11'. The top 60 edge of the seat should be flush with the floor top, and it receives the base 12 of the lower leg member 13. The base fits the seat 10, conforming to the shape thereof, so that it is firmly held and the upper part of the 65 base is preferably flush with the floor line so as to form no crack or crevice for receiving dirt. The leg 13 has a socket 14 at its upper part, and this is closed by a plug nut 15 which is fast to the leg 13, and is in its 70 largest part of the same diameter as the leg members, but has a shoulder 16 seating on the top of the member 13 so that the body of the plug nut 15 will extend downward 75 into the socket of the member 13. The nut 15 is fast to the member 13, and it might possibly be integral with the said member, but it is much easier to make it as shown.

The plug nut 15 receives a screw 17 which has a head 18 of the same diameter as the leg members, and this has means for turning it and the screw, the means shown being the common one of providing holes 19 which can receive some instrument by which the head and screw can be turned. The head 18 has an extension 20 which extends upward into the upper leg member 21 and which is rotatable with relation to said leg member. This forms a very secure connection which prevents the leg member 21 from wobbling. Thus it will 85 be seen that by turning the screw 17 up or down, the length of the leg comprising the two members 13 and 21 can be very easily 90 adjusted, even though the leg be in use to carry a support, and it can be done without 95 removing it from its floor seat.

The joint between the upper and lower leg members is covered by a sleeve 22 which is external of the leg members and fits them nicely, so that it serves as a brace to stiffen 100

the said members and also serves to conceal the joint between them. It will be noticed that the sleeve can be made to add an ornamental appearance to the leg, which is important because these legs are usually exposed, and are generally used in connection with a structure which is made as handsome as possible. The sleeve can be fixed in position by a set screw 23 which extends through 5 a wall of the sleeve and engages a seat 24 in the plug nut 15. The top of the upper member 21 is closed by a plug 25 to give stiffness to the member and to afford an anchorage for the bracket 26 or other structure 10 which it carries.

In the example given I have shown a three armed bracket 26 adapted to carry partitions 27, in a secure and handsome manner. One arm of the bracket has upturned narrow 20 flanges 28 to support a partition between them, while the other arms have each a single flange 31 disposed to lie on the inner sides of the partition members carried thereby. Headed pins 32 extend through the partition 25 members from the outside leaving only the ornamental heads exposed. The inner ends of the pins are tapped to receive screws 33 which extend through the flanges 31 and thus the partitions are securely supported 30 but the usual ugly fastenings are absent. The bracket can be secured to the leg by a screw 30 which extends down through the bracket and into a threaded hole 29 in the plug 25. The partitions can be braced by angle brackets 34 at the inner corners which may be secured by pins 32 and screws 33 as already 35 described.

From the foregoing description it will be seen how easy it is to adjust the length of the leg without disturbing its foundation or without removing the super-structure if the latter has been applied. The sleeve 22 is slipped 40 down or up, preferably down, to permit the head 18 to be turned, and this is all that is necessary to adjust the length of the leg, after 45 which the sleeve 22 is slipped back to the position shown in Figure 3 and fastened in place. Thus I provide a very strong simple leg which can be made highly ornamental 50 and which has the advantage of being easily adjusted.

It will also be seen that the whole partition support is simple, strong and handsome. This last feature is desirable in structures of 55 the kind referred to.

I claim:—

1. A supporting leg comprising a lower leg member having a base, a complementary upper leg member aligning with said lower leg member, a screw adjustable in the upper end 60 of the lower member, said screw having a head portion of a cross section corresponding to the adjacent parts of the two leg members and with an extension projecting into 65 the upper leg member, a sleeve freely slidable

over the joint between the upper and lower leg members, and means for fastening the sleeve.

2. A supporting leg for raised partitions comprising a lower leg member having a base, an upper leg member complementary to the lower member and carrying a partition supporting bracket, an internal screw connection between the two leg members, the thread whereof engages one member only, said screw having a head, the cross section of which corresponds to that of the adjacent leg members and with an extension projecting into the upper leg member, a sleeve freely slidable on the two leg members and disposed to cover the joint between them, and means for fixing the position of the sleeve.

In testimony whereof, I have signed my name to this specification this 18th day of November, 1927.

JOSEPH A. HOEGGER.
